UNITED STATES PATENT OFFICE.

CHARLES E. BIRD, OF MINNEAPOLIS, MINNESOTA.

SCALE-LEVER.

1,337,635.

Specification of Letters Patent. Patented Apr. 20, 1920.

Application filed May 26, 1919. Serial No. 299,949.

To all whom it may concern:

Be it known that I, CHARLES E. BIRD, a citizen of the United States, residing at Minneapolis, in the county of Hennepin 5 and State of Minnesota, have invented certain new and useful Improvements in Scale-Levers; and I do hereby declare the following to be a full, clear, and exact description of the invention, such as will enable others 10 skilled in the art to which it appertains to make and use the same.

My present invention relates to scale beams and levers, and has for its object to provide an improved knife edge pivot there- 15 for. Generally stated, the invention consists of the novel construction and arrangement of parts hereinafter described and defined in the claims.

So-called scale levers and beams are, in 20 fact, levers of one class or the other and in this specification, they will be referred to generally as levers.

The invention is illustrated in the accompanying drawings wherein like characters 25 indicate like parts throughout the several views.

Referring to the drawings:

Figure 1 is a plan view showing a portion 30 of a scale lever equipped with two knife-edge pivots in accordance with my invention.

Fig. 2 is a side elevation of the parts shown in Fig. 1, some portions being sectioned;

Fig. 3 is a vertical section on the line 35 3-3 of Fig. 2, some parts being in full;

Fig. 4 is a side elevation illustrating a somewhat modified means for adjustably 40 positioning the knife edge pivot in the lever; and Fig. 5 is a fragmentary plan view of the parts shown in Fig. 4.

The scale lever is indicated by the numeral 6, the same, as shown, having two pivot hubs 7 and 8 to give increased lateral 45 bearing in the knife edge pivots. The knife edge pivots 9 are formed with approximately semi-cylindrical surfaces 9^a, with knife edge wedge portions 9^b and longitudinal shoulders 9^c at the base of the wedge. Preferably, 50 the knife edge of the wedge 9^b is parallel to the shoulders 9^c and both are at a slight angle in respect to the basal line of the cylindrical surface 9^a, so that the pivot is given, in effect, a longitudinal taper.

55 The cylindrical surface 9^a of these knife edge pivots 9 fit cylindrical seats 10 formed

in the respective hubs 7 and 8, or any other suitable portion of the lever, and there will be space between these seats and the shoulders 9^c and wedges 9^b. Such spaces 60 are filled in with a hard filling material 11 which is preferably metal of low fusibility cast into the said space after the knife edge pivot has been properly positioned. As shown in Fig. 2, the seats 10 are formed 65 with radial anchor pockets 12 into which portions of the filling material 11 will run to positively anchor such filling material.

In Figs. 4 and 5, adjusting screws 13 are screwed through threaded seats in the lever 70 and into engagement with the opposite shoulders 9^c. By these screws, a knife edge pivot may be not only tightly seated in its seat 10, but its knife edge may be adjusted toward one or the other end of the lever 75 by oscillation of the pivot. When the said screws are used, they will be left in position while the filling material 11 is being cast into the seat to fill up the space, or, in some instances, the filling material might 80 be dispensed with and the said screws alone relied upon to hold the pivot. With these adjusting screws, it is possible to get the most accurate spacing between the edges of two pivots applied, as shown, for example, 85 in Fig. 4. The shoulders 9^c are therefore, useful in both of the illustrations above given, or even in other arrangements that might be employed. They afford means for positively and accurately holding the knife 90 edge pivots to the lever without in anyway marring the knife edge, and moreover, they permit ready substitution of new pivots when the edge of one is worn or damaged. Replacements may thus be very easily made 95 and the most accurate adjustments attained. The pivots, also, may be cheaply, yet very accurately milled to exact form. They permit the use of cylindrical seats in the lever which may, of course, be accurately and 100 cheaply made, whereas, the irregular form hitherto quite generally employed, has been very difficult to make and very expensive when accurately made.

What I claim is:

- 105 1. A knife edge scale pivot formed with a cylindrical portion, with a wedge-shaped portion and with shoulders at the base of said wedge shape portion.
2. The combination with a scale lever 110 having a cylindrical pivot seat, of a pivot inserted into said seat, said pivot having a

segmental cylindrical surface fitting said seat, having wedged portion that is spaced from said seat and having shoulders at the base of said wedge portion.

5. 3. The combination with a scale lever having a cylindrical pivot seat, of a pivot inserted into said seat, said pivot having a segmental cylindrical surface fitting said seat, having wedged portion that is spaced from said seat and having shoulders at the base of said wedge portion, and means applied to said lever within said seat and engaging said shoulders to securely hold said pivot in working position.

15 4. The combination with a scale lever having a cylindrical pivot seat, of a pivot inserted into said seat, said pivot having a segmental cylindrical surface fitting said seat, having wedged portion that is spaced from said seat and having shoulders at the

base of said wedge portion, and a hard metal cast into the said seat and filling the space between the same and the wedge and shoulders of said pivot.

5. The combination with a scale lever ²⁵ having a cylindrical pivot seat, of a pivot inserted into said seat, said pivot having a segmental cylindrical surface fitting said seat, having wedged portion that is spaced from said seat and having shoulders at the ³⁰ base of said wedge portion, and screws applied to said lever, projecting into said seat and engaging the shoulders of said pivot.

In testimony whereof I affix my signature in presence of two witnesses.

CHARLES E. BIRD.
